US00D405769S

United States Patent

[19]

Kondo et al.

[11] Patent Number: Des. 405,769

[45] Date of Patent: **Feb. 16, 1999

[54] ELECTRONIC COMPUTER

[75] Inventors: **Osamu Kondo**, Tokyo; **Masaaki Iino**, Saitama-ken, both of Japan[73] Assignee: **Kabushiki Kaisha Toshiba**, Kawasaki, Japan

[**] Term: 14 Years

[21] Appl. No.: 81,059

[22] Filed: Dec. 19, 1997

Related U.S. Application Data

[63] Continuation-in-part of Ser. No. 77,166, Jun. 18, 1997, which is a continuation of Ser. No. 57,746, Jul. 31, 1996, abandoned, which is a continuation-in-part of Ser. No. 68,488, Mar. 21, 1997, abandoned.

[57] CLAIM

The ornamental design for an electronic computer, as shown and described.

DESCRIPTION

FIG. 1, is a top, front and right side perspective view of an electronic computer showing our new design according to a first embodiment thereof;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof;

FIG. 8 is a front elevational view thereof in a closed position;

FIG. 9 is a right side elevational view thereof in the closed position;

FIG. 10 is a top plan view thereof in the closed position;

FIG. 11 is a top, front and right side perspective view of a second embodiment thereof;

FIG. 12 is a front elevation view thereof;

FIG. 13 is a top plan view thereof;

FIG. 14 is a bottom plan view thereof;

FIG. 15 is a rear elevational view thereof;

FIG. 16 is a right side elevational view thereof;

FIG. 17 is a left side elevational view thereof;

FIG. 18 is a front elevational view in a closed position thereof;

FIG. 19 is a top plan view in the closed position thereof; and,

FIG. 20 is a right side elevational view in the closed position.
